UNITED STATES PATENT OFFICE.

EUGENE S. HUFFMAN, OF ROCKFORD, ILLINOIS.

NICOTINE COLLECTOR FOR TOBACCO SMOKING.

Application filed October 20, 1924. Serial No. 744,572.

This invention relates to cigar and cigarette holders and pipes for smoking tobacco and has for its primary object the provision of improved means for collecting 5 nicotine from the smoke so that it will not be injurious to the health of the smoker. To this end my invention contemplates broadly the provision of a smoke stem or passage between the mouthpiece or bit and 10 the cigarette or cigar holder or the bowl of the pipe, as the case may be, constructed in a novel manner to provide a continuous or circuitous path for effecting deposit of the nicotine and other heavier constituents 15 in the smoke.

My invention also aims to provide a nicotine collector of the character described which is removable for cleaning or replacement and which may be effectually embodied in various forms of holders or parts. 20 In the preferred embodiment the nicotine collector is in the form of a filler tube which may be either inserted into a holder or may itself constitute a part of the holder such 25 for example as the stem, to the opposite ends of which the bit and the cigar, cigarette or tobacco bowl may be attached.

A further object is to provide an improved nicotine-collector characterized by a 30 tubular body providing a tobacco smoke passage and having transverse indentations or obstructions for intercepting the smoke. In the preferred embodiment these obstructions are formed when the body is plastic 35 at least at localized spots, by pressing in the body preferably but not necessarily from diametrically opposite points with a pointed implement and bringing the pressed in portions into contact one with the other, thereby 40 providing a transverse obstruction having curved or sloping sides and dividing the single passage into two restricted passages. By arranging these transverse restrictions in relatively angular relation the tubular 45 passage is divided into a plurality of small compartments or inter-passages on the walls of which the heavier constituents such as nicotine will be deposited.

A further object is to provide in a tobacco 50 smoking device of any kind, a nicotine-collector embodying the broad characteristics disclosed herein.

Still another object is to devise a simple and commercially practical form of holder 55 for a nicotine-collector embodying my invention.

Other objects and attendant advantages will be appreciated by those skilled in this art as the invention becomes better understood by reference to the following description when considered in connection with the 60 accompanying drawings, in which—

Figures 1 and 2, are a side elevation and a longitudinal section respectively through a cigarette or cigar holder embodying my 65 invention;

Figs. 3 and 4, are enlarged cross-sections taken on the lines 3—3 and 4—4 respectively of Fig. 2;

Fig. 5, is a side elevation of a modified 70 form of my invention;

Fig. 6, is a cross-section taken on the line 6—6 of Fig. 5;

Fig. 7, is a side elevation of another modification of my invention; 75

Fig. 8, is a cross-section taken on the line 8—8 of Fig. 7; and

Fig. 9, is a side elevation partly in longitudinal section of still another modification 80 of my invention.

Referring to the embodiment shown in Figs. 1 to 4 inclusive, this comprises a cigar or cigarette holder the stem or body portion of which, designated generally by 11, is formed integral with the bit 12, and the 85 tobacco holder (in this case for a cigar or cigarette) is in the form of a socket piece 13 having a threaded end 14 screwed into the body 11. These parts may be made of any suitable material or composition, it being preferred in practice to make them of a bakelite composition.

The smoke passage in the body 11 is bored out as at 15 to receive a tubular nicotine-collector, designated generally by 16. In 95 this embodiment of my invention the tubular member may be of any suitable material and in the present instance is of glass. It is shaped interiorly to provide a series of inter-passages 17 connected by restricted 100 openings 18 which cause the smoke to travel in a sinuous or circuitous path and to deposit the heavier constituents such as the nicotine. In this form of my invention the 105 passages 18 are formed when the glass is in a plastic condition at localized spots, by pressing in the glass at diametrically opposite points until the pressed in portions 19 are brought into approximate contact. These pressed in portions 19 provide transverse indentations or obstructions thus 110 dividing the tubular member 11 into the

inter-passages 17 and restricted passages 18 above-mentioned and provide obstructing walls on which the nicotine will be collected. These transverse obstructions are formed at 5 longitudinally spaced points in angular relation with respect to adjoining obstructions, in this instance at right angles as clearly shown in Figs. 3 and 4. By reason of this construction the nicotine and any 10 heavy constituents in the smoke will be deposited and collected by the obstructing walls and within the tubular member 16 by reason of the sinuous path imposed by its interior construction, without appreciably 15 increasing the draw through the stem.

It will be noted that in this form of my invention the tubular nicotine collector is 20 removably held in position by the socket piece 13 and may be quickly and readily removed from the body 11 for cleaning or replacement. Thus by the use of refill nicotine-collector tubes such as disclosed in this embodiment of my invention, a cigarette or 25 cigar holder or any kind of device used for smoking tobacco may be readily kept clean and free from injurious deposits. By constructing the tubular nicotine collector in this manner it may be produced at a comparatively low cost and the refill expense 30 is comparatively small to the discriminating user considering the advantages gained. Furthermore with this construction the holder proper may be embodied in any shape or form desired or in bakelite or other compositions of different colors. In practice I 35 have found it very desirable to use a light colored bakelite resembling amber which is quite transparent so as to make the nicotine-collector visible to the extent of clearly showing the contents collected. Thus the 40 user may detect at a glance when it is necessary to remove the collector tube for cleaning or replacement.

In the embodiment shown in Fig. 5 the 45 nicotine-collector 21 is made integral with the socket piece 22 and bit 23. In this form of the invention the interior of the smoke passage is substantially identical with that in the tubular member 16, except as to dimensions. This form provides a unitary article 50 which may be made from any plastic or ductile material suitable for the purposes in mind. In this form as in that first described the nicotine is collected or deposited on the interior walls as a result of the shape thereof.

In Figs. 7 and 8 I have shown a modified 60 form of the invention in which the holder proper, designated by 24, is in one piece with the smoke passage bored out somewhat larger than ordinarily as indicated by 25. This smoke passage is divided by transverse obstructions in the form of pins 26 at longitudinally spaced points and in angular relation 65 simulating the transverse indentations

19 described above. The pins 26 are designed to function similarly to said indentations 19, that is, they provide transverse obstructions and divide the principal smoke passage into restricted passages and inter- 70 passages. This illustrates that I do not wish to confine myself to an integral structure for the nicotine-collector proper but that substantially the same result might be obtained by a built-up construction. 75

In Fig. 9 I have shown still another modification in which a nicotine-collector tube designated generally by 27 similar to the tube 16 except that it has flanged ends 28, provides the stem proper and has attached to its opposite ends a socket piece 29 and a bit 31. In this form of the invention the socket piece and bit may be attached to the stem part 27 in any suitable manner as for example that shown in which the socket 80 piece and bit respectively have a part 32 entering the adjacent end of the tubular piece 27 and are detachably connected thereto by a coupling nut 33 which engages the flange 28 as clearly shown. 85

It should be understood that my invention is not to be limited to the kind of material making up the nicotine-collector, nor to the number, arrangement and form of the transverse smoke obstructions, unless specifically 90 stated in certain claims. My invention in its broader aspect comprehends means of the character disclosed, or equivalent means, for collecting nicotine from tobacco smoke in any kind of a smoking device, as, for example, a cigarette or cigar holder, or a pipe. It should be understood, therefore, that in 95 practice, many changes might be made in the materials, size and shape of parts without departing from the spirit and scope 100 of the invention as expressed in the appended claims, in which— 105

I claim:

1. As a new article of manufacture, a nicotine-collector comprising a tube adapted to be interposed in the smoke passage of a pipe, cigar or cigarette holder, said tube having at longitudinally spaced points pressed in portions each of which provides a restricted smoke passage at the periphery of the tube, the pressed in portions at the longitudinally spaced points being in relatively angular relation whereby said restricted smoke passages are in non-alignment longitudinally and cause the smoke to travel in a sinuous path. 110

2. As a new article of manufacture, a nicotine-collector comprising a tube adapted to be interposed in the smoke passage of a pipe, cigar or cigarette holder, the tube having at longitudinally spaced points transversely pressed in portions which provide restricted smoke passages between each pressed in portion and the inner periphery of the tube, the pressed in portions at ad- 115

joining longitudinally spaced points being in non-alignment longitudinally whereby to provide a sinuous smoke passage.

3. A cigar or cigarette holder comprising a stem or body portion having a bit at one end and a smoke passage bored to receive a nicotine-collector, a socket piece connected with said stem, and a nicotine-collector adapted to be inserted into said bored pas-

sage and to be retained therein, the nicotine-collector being in the form of a tube open at its ends and having at longitudinally spaced points opposed pressed in portions in contact at their inner ends providing transverse smoke obstructions and leaving separated, restricted smoke passages at the periphery of the tube.

EUGENE S. HUFFMAN.
